F. MANKEY.

MOLDING.

No. 17,135.

Patented Feb. 22, 1887.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 17,135, dated February 22, 1887.

Application filed July 1, 1886. Serial No. 206,872. Term of patent 7 years.

To all whom it may concern:

Be it known that I, FREDERICK MANKEY, of Williamsport, Lycoming county, Pennsylvania, have invented and produced a new and original Design for Ornamental Trims or Moldings, of which the following is a specification, reference being had to the accompanying photograph, forming part hereof.

My design relates to an ornamental trim or molding in the form of a bar or band; and it consists in the configuration thereof, substantially as herein represented.

On each edge of the bar or band appear regular convexities or scallops A, the scallops on one edge being opposite those on the other edge. On the middle portion of each scallop is a rectangular projection, B. Through the bar appear apertures C. Said apertures have four inwardly-convex sides, as E F G H, and two straight and parallel sides, as I J. The straight sides stand transversely the bar. Said apertures are disposed symmetrically between the scallops on opposite edges of the bar, and are spaced at regular intervals along said bar.

Upon the face of the bar appear the following grooves or channels, viz: an inclined groove,

K, extending from the point of junction of two scallops A to the angle between the sides E I of an aperture C; an inclined groove, N, extending from the point of junction of the 30 rectangular projection B and scallop A to the angle between the sides E F of the aforesaid aperture; a lenticular groove or channel, L, extending from the angle of the sides F J of the aforesaid aperture to the angle of the sides 35 I H of the next adjacent aperture, and an inclined groove, M, extending from the angle of the sides G H of said first-mentioned aperture to the junction of projection B and scallop A on the opposite edge of the bar. 40

I claim—

The design for an ornamental trim or molding, substantially as herein shown and described, which consists in the scallops A, having rectangular projections B on opposite edges 45 of said trim, the openings C at regular intervals in said trim, and on the face thereof the lenticular channel L.

FREDERICK MANKEY.
